BUCKLE

Frank A. Best, Windsor, Ontario, Canada

Application July 29, 1943, Serial No. 496,533

2 Claims. (Cl. 24—77)

This invention relates to buckles and more particularly, to buckles for flexible straps, belts or the like.

One object of the present invention is to provide a simple, sturdy and efficient buckle which effects a gripping action mainly by surface friction between the strap or belt and the coacting faces or edges of the buckle elements, and without recourse to penetration of the strap or belt by teeth, prongs, tines or similar fabric-piercing means.

Another object of the invention is to provide a buckle of the character indicated, wherein the strap or belt is gripped by cooperation between relatively movable buckle parts and wherein the said buckle parts are movably attached to each other in simple and secure fashion, and in such manner that tension on the strap or belt increases the gripping action of the buckle parts.

Another object of the invention is to provide a buckle which is readily assembled from two separately formed metal stampings with a minimum number of machine operations or other labor costs.

These objects, and others not specifically mentioned but which will be apparent to those skilled in the art from a consideration of this specification and the accompanying drawing, are attained in a manner now to be described. Although said drawing illustrates the essential features of my invention, it should be understood that the drawing is not to be regarded in a limiting sense as it illustrates merely one structure in which the inventive concept is embodied. In said drawing,

Fig. 1 is a top plan view of my buckle in attached and gripping position;

Fig. 2 is a sectional view taken on the line 2—2 of Fig. 1;

Fig. 3 is a top plan view of the two elements forming the buckle of Figs. 1 and 2, said elements being separated for clarity of illustration;

Fig. 4 is a side elevation of the buckle shown in the preceding views, and

Fig. 5 is a side elevation, showing the buckle attached to the butt end of a strap or belt, as in Figs. 1 and 2, but showing the free end of the strap or belt in a partially gripped condition.

The buckle shown in the drawing is assembled from two members, here illustrated in Fig. 3 as a generally rectangular main frame 11 and a separately formed rectangular hollow link 12. The main frame comprises two opposed side bars 13 and 14, and two opposed end bars consisting, respectively, of a rear end bar 15 and a

front end bar 16. Forwardly spaced from the rear end bar 15 and attached at its ends to the side bars 13 and 14 is a cross bar 17 around which the butt end of a strap or belt 18 is looped, the loop being secured in any suitable way, as by rivets, snap members, or by the stitching 19 here shown (Fig. 2).

Integrally united with the main frame 11, and extending rearwardly from the front end bar 16 is a channelled tongue 22, upwardly concaved to receive and retain, in the concavity thereof, the cross bar 23 of the link 12. The link swings loosely and freely in the channel, and the channel provides a firm support for the link over substantially the entire width of the buckle, in contradistinction to previously known types of buckles where movable links are supported only at corners or lateral edges.

In use, the free end 25 of the strap or belt is inserted upwardly through link 12 and past the adjacent front edge of end bar 16. The assembly (Fig. 5) is now in what may be termed a preliminary gripping stage, as tension on the strap or belt in the direction of the arrow A swings the link from the position shown in Fig. 4 to that of Fig. 5. The strap or belt is thus gripped between link 12 and end bar 16, and increasing tension on the strap or belt actually increases the gripping force of the buckle by urging the link 12 closer to a horizontal position, with the consequent pinching of the strap more tightly between the free edge of the link and the end bar 16. As previously noted, the tensional force is distributed uniformly to the buckle, being borne evenly by the channelled tongue 22 along a line transversely of the buckle.

In the position shown in Fig. 5, the strap or belt may be used to support loads and will not slip while the tension is maintained. It is readily removed or adjusted as to length by slackening off the tension and making the desired adjustment. A more definite and secure locking effect, and a neater assembly, is achieved by advancing the free end 25 of the strap or belt from the position shown in Fig. 5 to that shown in Fig. 2, which is accomplished merely by inserting said free end under the rear end bar 15 of the buckle and drawing it to the left of Fig. 2 as far as it will go. This position is more appropriate, for example, when the buckle is used as a part of a belt for wearing apparel.

The main frame 11 of the buckle, and the link 12 thereof, are preferably formed from a strip of sheet metal by a stamping operation. Formation of the link is extremely simple and need not

be specifically described. As its side and end members are symmetrically disposed with respect to longitudinal and transverse center lines, it can be handled and assembled in the shortest possible time, there being only a minimum of time lost in orienting the link properly with respect to its seat in the channelled tongue 22 of the main frame member 11.

Fabrication of the main frame 11 is also a simple operation. One part of the stamping die 10 knocks out a rectangle of metal, leaving the free space 21 (Fig. 3). Another part of the stamping die cuts a U-shaped slot, defining the cross bar 17. The metal partially surrounded by the U slot is simultaneously mechanically deformed 15 into the channelled tongue 22 with two objects in view; namely, to provide a retaining seat for link 12, and to leave a clearance space 28 through which the strap or belt loop 18 passes (Figs. 2 and 3). The main frame 11 and the link 12 may therefore be formed by a single stroke of the stamping die. Originally, the vertical clearance between the front edge 29 of the channelled tongue 22 (Fig. 5) and the side bars 13 and 14 of the main frame is large enough to permit ready insertion of the link 12 to its seat in the tongue concavity, but after such insertion, the tongue is forced upwardly a sufficient distance to prevent accidental separation of the link from the main frame.

To those skilled in the art to which the present invention relates, further features and advantages of buckles embodying such invention will be evident from the foregoing description of one such embodiment.

What I claim is:

1. A buckle for attaching two strap ends, com-

prising a body member and a link member carried by said body member, said body member consisting of a generally rectangular frame having two side bars, two end bars, and a cross bar 5 integrally connected, at its ends, to said side bars and disposed parallel to and between said end bars, one of said end bars having integral with the inner edge thereof a channelled tongue, said tongue having a free edge extending towards but spaced from said cross bar, said link member being of rectangular open frame form with two spaced cross bars, said link being movably dependent from said channelled tongue, and a cross bar of said link being confined within said channelled tongue.

2. A buckle for attaching two strap ends, comprising a metal body member, and a link member swingably depending from said body member, said body member consisting of a generally rectangular frame having two longitudinally disposed side bars, a front end bar and a rear end bar integral, respectively, with the front and rear ends of the side bars, a cross bar integrally connected at its ends to said side bars, and disposed parallel to and between said end bars, so as to define, within the side and end bars, forwardly and rearwardly disposed apertures, said front end bar having integral with the inner edge thereof a tongue of channelled contour having a free edge extending towards but short of said cross bar, said link member being of hollow frame form having spaced side and end members, one side member of said link being pivotally confined within the concavity of said channelled tongue and the other side member of said link being freely dependable in oscillatory relationship.
